W. F. WARDEN.
FAN VENTILATOR.
APPLICATION FILED JUNE 24, 1911.

1,117,287.

Patented Nov. 17, 1914.

UNITED STATES PATENT OFFICE.

WILLIAM F. WARDEN, OF AKRON, OHIO, ASSIGNOR TO THE BURT MANUFACTURING COMPANY, OF AKRON, OHIO, A CORPORATION OF OHIO.

FAN-VENTILATOR.

1,117,287.

Specification of Letters Patent.

Patented Nov. 17, 1914.

Application filed June 24, 1911. Serial No. 635,199.

To all whom it may concern:

Be it known that I, WILLIAM F. WARDEN, a citizen of the United States, residing at Akron, in the county of Summit and State 5 of Ohio, have invented a certain new and useful Improvement in Fan-Ventilators, of which the following is a full, clear, and exact description, reference being had to the accompanying drawings.

10 This invention relates to ventilators and has for its especial object the provision of a cheap and serviceable device of this class comprising a fan for the positive production of a draft and a damper for regulating said 15 draft, said regulating means being so formed as to offer the slightest possible opposition to the fan when in open position.

Another object is the provision in a device of this kind of a fan driving mechanism, which shall be noiseless and wear 20 proof, and at the same time shall be adjustable to vary the speed of the fan as required. Other objects and advantages will appear from the following description and claims.

25 One embodiment of my invention is illustrated in the accompanying drawings in which—

Figure 1 is a vertical sectional view of the ventilator, the fan and driving mechanism 30 being shown in section, and Fig. 2 is a sectional view of the fan and driving mechanism drawn to larger scale.

Describing the parts of the aforesaid drawing by reference numerals, 1 denotes the 35 lower section and 2 the upper section or top of a ventilator. The lower section is preferably cylindrical and is adapted to be applied to the roof of a building to provide a tubular air-shaft therefor. The upper section is shown as a conical roof, the lower edge 3 of which projects beyond and overhangs the lower section and is spaced vertically therefrom to provide an annular discharge port. Said upper section or top is 40 supported upon the lower section by a plurality of vertical braces 4 suitably attached adjacent the upper edge of the lower portion, as by rivets 5. The upper ends of these braces are bent downward at the angle of 45 the top section, as shown at 6, and secured to the top by rivets. The outer ends of these downwardly bent portions are carried outward beyond the edge 3 of the top, bent vertically downward as at 8, and thence inward

55 at substantially the level of the top of the lower section, as shown at 9, and finally terminated in a short upturned lug 10. Suitably secured to the extended portions of these braces as by rivets 11 is the cylindrical shield 12. A frusto-conical deflector plate 13 having an upturned cylindrical flange 14 is secured substantially level with the top of the lower section of the ventilator, preferably by means of a single rivet passing through the upturned lug 10, the flange 14 60 and the vertical brace 4 as shown. Other deflectors 15 may be secured to the braces 4, one of these being illustrated. Each of the braces 4 is offset away from the edge of the lower section at 16 in order to provide a seat 70 for the conical damper now to be described.

Vertically positioned in the axis of the ventilator is a round post, attached at its upper end to the peak 18 of the top 2, and supported at its lower end by braces attached 75 to the sides of the lower section. A sleeve 20 having an upwardly flaring flange 21 is slidably mounted on this post and a conical metal plate is riveted to this flange, said plate being of slightly greater diameter than 80 the lower section 1, and adapted to seat upon the upper edge 23 thereof to form a damper. Braces 24 cross the upper portion of the damper and slide upon the post 19 at 25, preventing wabbling. Chains 26 passing 85 over pulleys 27 are secured to the damper and permit operation thereof from below, said chains preferably containing fusible links 28 operative to close the ventilator in 90 case of fire.

Conveniently secured inside the lower section, as by means of a sleeve 29 on the post 17 and a bracket 30 on the brace 19, is a countershaft 31 projecting radially from the post, and carrying a friction wheel 32 and a 95 belt pulley 33. Rotatably mounted on the post 17 is a fan hub 33, said hub having radial blades 34 attached thereto, and having at its lower end a flat friction plate 35 adapted to rest upon the friction wheel 32 100 and to be driven thereby. The hub may conveniently contain a lubricant chamber 36.

For the purpose of increasing the adhesion between the friction wheel and plate, a spring 37 may be employed compressed between a collar 38 attached to the post and a suitable bearing 39 supported by arms 40 from the fan hub 33. I have shown a ball

bearing consisting of two grooved plates with balls between them as being a cheap and efficient construction.

For the purpose of stopping the fan in case of fire, or when, for any reason, the damper is closed, means may be provided for raising the friction plate away from the wheel. Such means may conveniently consist of a lever 41 pivoted to a bracket 42 clamped upon the shaft 31, or other convenient support, and adapted to be contacted by an adjustable stop 43 clamped to one of the chains 26. This stop is so positioned upon the chain that as the damper approaches its closed position, the lever 41 is raised so as to draw the roller 44 against the friction plate and lift it off the wheel 32. At the same time it will be noted that this action does not occur until the damper is very nearly closed, thus allowing a wide range of regulation of the draft before the power is cut off from the fan. If desired, a second stop 45 may be attached to the chain so that in case the lever should stick, it can be positively drawn down out of engagement with the plate.

The speed of the fan can be adjusted by setting the friction wheel 32 nearer to, or farther from the post 17, the collar 46 and bracket 30 being properly loosened and reset. The conical shape of the damper is of advantage when in open position, since it serves to direct the air current in proper direction without the formation of eddies. In case of fire the fusible links promptly melt, allowing the damper to close, and at the same time stopping the fan in the manner above described.

Having thus described my invention, what I claim is:

1. A ventilator comprising in combination a cylindrical lower section adapted to be supported upon the roof of a building, a vertical post axially supported in said section, a shaft extending radially from said post, a friction wheel rotatably mounted on said shaft, a fan rotatably mounted on said post and having a friction plate adapted to rest upon said friction wheel, means for driving said friction wheel, a lever mounted beneath said plate, a roller carried by said lever, and means for raising said lever so as to force said roller into engagement with said plate and raise said plate out of contact with said friction wheel.

2. A ventilator comprising in combination a cylindrical lower section adapted to be supported upon the roof of a building, a vertical post axially supported in said section, a shaft extending radially from said post, a friction wheel rotatably mounted with its axis substantially at right angles with said post, a fan rotatably mounted on said post and having a friction plate adapted to rest upon said friction wheel, means

for driving said wheel, a rotatable anti-friction member beneath said plate, and means for elevating said member against said plate so as to raise said plate from said wheel.

3. A ventilator comprising in combination a cylindrical lower section adapted to be supported upon the roof of a building, a vertical post axially supported in said section, a fixed shaft extending radially from said post, a friction wheel rotatably mounted on said shaft, a fan rotatably mounted on said post and having a friction plate adapted to rest upon said friction wheel, means for driving said wheel, a bracket carried by said shaft, a lever pivoted to said bracket, antifriction means carried by said lever beneath said plate, and means for inclining said lever to shift said antifriction means into engagement with said plate and elevate said plate from said wheel.

4. A ventilator comprising, in combination, a lower section adapted to be supported upon the roof of a building, a top section overlapping and spaced from said lower section, a vertical post running axially through both sections, a damper slidably mounted on said post, and adapted, when lowered, to close the passage through the ventilator and when raised to define a free exhaust port, an exhaust fan rotatably mounted on said post, a downwardly facing friction plate carried by said fan, a friction wheel journaled upon an axis substantially perpendicular to said post and disposed beneath said plate, means for rotating said wheel, a lever pivotally supported by said post beneath said plate, antifriction means carried by said lever, flexible tension means for raising and lowering said damper, and connections between said lever and said tension means for elevating said antifriction means against said plate and disengaging the same from said friction wheel as said damper approaches a position of closure.

5. A ventilator comprising, in combination, a hollow open section adapted to be supported in upright position upon the roof of a building, a vertically movable damper plate adapted, when lowered, to rest upon the upper end of said section and close the passageway therethrough, pulleys fixedly supported as regards said lower sections, flexible tension means passing over said pulleys and engaging said damper plate whereby a downward pull upon said tension means will raise said damper plate, an exhaust fan rotatably mounted in said lower section with its axis substantially vertical, a downwardly facing friction plate carried by said exhaust fan, a friction wheel journaled upon a substantially horizontal axis and disposed beneath said plate, means for driving said friction wheel, a rotatable anti-

friction member beneath said plate, and connections between said antifriction member and said tension means whereby the movement of said damper to closed position will 5 elevate said member against said plate so as to raise said plate from said friction wheel.

6. A ventilator comprising, in combination, a hollow open section adapted to be supported in substantially vertical position 10 upon the roof of a building, a damper member supported above said section and adapted, when lowered, to close the passage therethrough, an exhaust fan journaled upon a substantially vertical axis beneath said

damper, means for driving said fan, means 15 including a fusible element for maintaining said damper in elevated position, and connections between said damper and fan for disengaging said fan from said driving means upon the approach of said damper to 20 closed position, said connections being independent of said fusible element.

In testimony whereof, I hereunto affix my signature in the presence of two witnesses.

WILLIAM F. WARDEN.
